SIMON KROTOSCHIN, OF LEIPZIG, GERMANY.

PLACARD.

Application filed September 21, 1927, Serial No. 221,076, and in Germany August 12, 1927.

My invention relates to advertising posters, placards and the like, such as are used especially as coverings for the rear walls of store-windows, showcases and similar spaces. It is known to provide such coverings in the form of corrugated sheets of pasteboard having an impression for advertising purposes, whereby the corrugations of said pasteboard are vertically directed. The employment of 5 corrugated sheets of pasteboard for this purpose offers the advantage that the form of said coverings may be easily adapted to the various forms of the backgrounds of store-windows, show-cases and the like, yet providing sufficient rigidity for the body of the 10 poster or placard in vertical direction in order to prevent the same from collapsing.

Essentially the same effect may be obtained by using ordinary sheets of pasteboard, car- 20 ton or a similar material of sufficient rigidity, if the said material, which is preferably used in the form of sheets of greater lengths obtainable on the market is subdivided by means of score-lines, creases, incisions or the like 25 into numerous fields or sections which are hinged to each other along the said score-lines or the like. The size of the several fields or sections may be chosen according to the special advertising purpose. These fields or sec- 30 tions may thereby be either of the same or of different widths, and the impressions may be made thereon either in such a manner that all fields or sections are provided with the same impression or that several fields or sections 35 are provided in groups with impressions. The impressions made in this manner upon the several groups of fields or sections will then continuously repeat themselves in case of a continuous manufacture of the entire body of the poster, placard or the like. The 40 upper edge of the several fields or sections or of the several groups of fields or sections may be made of plain or ornamental form according to the special advertising purpose.

The several fields or sections of the advertising poster or placard are preferably further subdivided into stripes of smaller width which likewise extend in vertical direction to the vertical or standing-up edges or trans- 45 versely to the longitudinal direction of the sheet of pasteboard forming the poster or placard. This further subdivision of the fields or sections may likewise be accomplished by means of score-lines, creases, in-

cisions or the like which preferably do not 55 weaken the material at these places to the same extent as the score-lines, creases or incisions which separate the several fields or sections of the poster or placard. By this the effect will be obtained that on the one hand 60 the piece of pasteboard which is required for a poster or placard for a special use may be more easily separated from the continuous sheet of pasteboard and on the other hand 65 the flexibility of the several fields or sections as a whole will be essentially increased, so that the entire sheet of pasteboard may also be easily rolled up, preferably with the printed surface directed towards the inside. 70

In the accompanying drawing I have repre- 75 sented constructional forms of a poster or placard according to my invention,

Fig. 1 being a diagrammatical front view of the new placard,

Fig. 2 a top view taken on the placard of 75 Fig. 1 in properly bent condition,

Fig. 3 a front view of a modified form of placard,

Fig. 4 a top view taken on the placard of 80 Fig. 3 in properly bent condition,

Fig. 5 an enlarged horizontal section through two adjacent fields or sections of the placard as shown in Figs. 3 and 4.

In the modification of the placard as shown in Figs. 1 and 2 the body 1 of the placard is supposed to be cut off from a continuous sheet of pasteboard or carton of some greater length, said body 1 consisting of five fields or sections 1^a which are separated from each other by a proper number of vertically di- 85 rected score-lines, creases or incisions 2 which serve as a hinge or pivotal connection between adjacent fields or sections 1^a. The score-lines, creases or incisions 2 are worked into the body 1 of the placard alternately 90 from the one and the other side in order to permit a bending or swinging of the several fields or sections 1^a towards either side, so that the placard as a whole may be folded together and put up within a space of relatively 95 limited dimensions. By reason of this sub- 100 division of the body 1 of the placard into a greater number of fields or sections the placard may be easily made to follow the corners and walls of a display window, show-case or the like, by using the score-lines 2 for prop- 105 erly bending the placard so that the several fields or sections 1^a may be placed in any

desired angle with respect to each other in order to follow the conformation of the walls of a store-window, show-case or the like.

In the modified form of the placard as shown in Figs. 3 and 4 the adaptability of the placard to different forms of backgrounds will further be enhanced by having the several fields or sections 1^a further subdivided into a plurality of stripes 3 of relatively small width, which besides the score-lines or creases 2 may be made by incisions 3^a worked into the rear surface of the body 1 of the placard in such a manner that said incisions will extend not to the full depth of the material. In contradistinction to the arrangement shown in Figs. 3 and 4 the front surface of the placard will in this case be of entirely smooth conformation as may be seen from Fig. 5. By subdividing the body 1 of the placard by means of the score-lines or creases 2 as shown in Figs. 2 and 4 the advantage is obtained that the several fields or sections 1^a may be folded or bent in either direction while the incisions 3^a as shown in Fig. 5 will solely serve to facilitate bending of the surfaces of the several fields or sections 1^a in one direction. The fact that the score-lines or creases 2 will present themselves as elevations on the front surface of the placard, as shown at three places in Fig. 4, is no disadvantage of this modified form of the placard, since these elevated lines will in no way disturb the good appearance of the impressions or pictures on the front surface of the placard, especially if a greater number of fields or sections 1^a with uniform impressions or with impressions in a single color is employed. These score-lines or creases will rather serve to provide a pleasing interruption of the entire surface of the picture or impression. In either case the lines or incisions 3^a are of such conformation that they do not weaken the body of the placard to the same extent as the score-lines or creases 2 which separate the several fields or sections 1^a of the placard. It will also be possible, however, to provide incisions or cuts in the manner as shown at 3^a in Fig. 5, at small distances from each other all over the length of the placard without providing pronounced score-lines or creases as shown at 2 in Figs. 1 to 4. The height of the placard, that is the dimension of the same in vertical direction, or what is the same in the direction of the score-lines or creases 2 and the incisions 3^a, is preferably chosen in accordance with the average height of the rear wall of the store-window, show-case or the like for which the placard is intended to serve as a covering.

The material which is used for making the placard is ordinarily supplied in form of relatively short pieces by the pasteboard or carton factories. These pieces of pasteboard or carton may be pasted according to my invention one onto the other in the placard

factory, where also the score-lines, creases or incisions are applied and the impressions made on the front surface of the placard. In order to avoid bulks at the places, where the several pieces are united with each other by pasting, the edges of the respective pieces are sharpened or cut obliquely, or the bulks caused by two overlapping edges of adjacent pieces of pasteboard or carton may be remedied by applying a proper pressure thereto so that they will practically disappear by being smoothened out.

By providing the placard or wall covering in the form of a continuous sheet it will be possible to obtain the piece which is desired in order to cover a store-window or show-case of given dimensions, by a mere performance of cutting the same off a continuous sheet of pasteboard or the like, whereby the cut is preferably made along one of said score-lines, creases or incisions. The placard according to my invention may serve in essentially the same manner as is possible with the known placards which are made of corrugated pasteboard by means of which projecting as well as recessed parts of store-windows or show-cases as well as arched parts, columns or similar curved surfaces may conveniently be decorated, without, however, endangering the good appearance of the placard or of the inscription or pictures thereon by ruptures, gaps, dents, or other mutilations of the surface. Furthermore, a placard which is made according to Figs. 3 to 5, even if it consists of rigid material, may easily and conveniently be rolled up. In addition to this, the placard may also be folded together along the score-lines or creases 2 which separate the adjacent fields or sections 1^a, thus reducing its volume, which may be desirable for shipping purposes.

I claim:—

1. An advertising placard serving especially as a covering and a background for store-windows, show-boxes and the like comprising a sheet being subdivided into a plurality of sections by means of score-lines which are directed transversely to the longitudinal direction of the placard, the several sections being further subdivided into narrow stripes by means of secondary score-lines.

2. An advertising placard serving especially as a covering and a background for store-windows, show-boxes and the like comprising a sheet being subdivided into a plurality of sections by means of score-lines which are directed transversely to the longitudinal direction of the placard and pressed into the said sheet alternatively from the one and the other side of the said placard, the several sections being further subdivided into narrow stripes by means of secondary score-lines.

3. A placard comprising a sheet being subdivided by means of score-lines into a plurality of sections which are provided with ad-

vertising matter and with incisions being arranged parallel to the said score lines and subdividing each of said sections into a plurality of narrow stripes.

5 4. A placard comprising a sheet being subdivided into a plurality of sections by means of score-lines which are directed transversely to the longitudinal direction of the placard, the said sections being provided with advertising matter on their front sides and with incisions on their rear sides subdividing said sections into narrow stripes.

10 5. A placard comprising a sheet being subdivided into a plurality of sections by means of score-lines which are directed transversely to the longitudinal direction of the placard, each section being subdivided by means of secondary score-lines into narrow stripes,

said secondary score-lines being less pronouncedly applied than the score-lines which 20 subdivide the sheet into the sections.

6. A placard comprising a sheet being subdivided by means of score-lines presenting themselves as elevations, each of said sections being subdivided by means of secondary 25 score-lines into a plurality of narrow stripes.

7. A placard comprising a sheet being subdivided into a plurality of sections by means of score-lines presenting themselves as elevations, each of said sections being provided 30 with advertising matter on its front side and with incisions on its rear side, such incisions subdividing each section into a plurality of narrow stripes.

In testimony whereof I affix my signature.
SIMON KROTOSSHIN.
